UNITED STATES PATENT OFFICE

137,739

DESIGN FOR A GIMBAL

Ernest William Drescher, Manheim Township,
Lancaster County, Pa.

Application February 18, 1943, Serial No. 109,574

Term of patent 7 years

(Cl. D42—7)

To all whom it may concern:

Be it known that I, Ernest William Drescher, a citizen of the United States, residing in Manheim Township, in the county of Lancaster and State of Pennsylvania, have invented a new, original, and ornamental Design for Gimbal, of which the following is a specification, reference being had to the accompanying drawings, forming part thereof.

Fig. 1 is a plan view of a gimbal showing my new design and Fig. 2 is a side elevational view, the outer casing being shown in section in order that the configuration of the interior parts of the gimbal may be clearly illustrated.

I claim:

The ornamental design for a gimbal, as shown and described.

ERNEST WILLIAM DRESCHER.
